TO UNION PAPER BAG MACHINE COMPANY, OF PHILADELPHIA, PENNSYLVANIA,
A CORPORATION OF PENNSYLVANIA.

FEED MECHANISM.

1,029,760.

Specification of Letters Patent. Patented June 18, 1912.

Original application filed July 10, 1907, Serial No. 383,083. Divided and this application filed September 28, 1909. Serial No. 519,983.

To all whom it may concern:

Be it known that we, WILLIAM A. LORENZ and JOSEPH MERRITT, citizens of the United States, and residents of Hartford, in the 5 county of Hartford and State of Connecticut, have invented certain new and useful Improvements in Feed Mechanism, of which the following is a full, clear, and exact specification.

10 The object of this invention is to provide automatic mechanism for feeding, delivering, or transferring paper bags, envelops, blanks therefor, or sheets of paper and similar articles to various kinds of machines for 15 folding, printing, or otherwise manipulating such articles.

An important feature of the invention is its capacity for accurately and uniformly 20 registering such articles in the mechanism to which they are delivered, even though received irregularly, or at different speed from that of the machinery to which they are to be transferred.

This application is a division of our prior 25 joint application Serial No. 383,083, filed July 10, 1907, for improvements in paper bag machines.

In the embodiment of this invention shown in the accompanying drawings, Figure 1 is 30 a plan view partly in section. Fig. 2 is an end view of what is shown in Fig. 1 projected from the left hand end thereof. Fig. 3 is an end view of what is shown in Fig. 1, projected from the right hand end thereof. 35 Fig. 4 is an end view in vertical section taken in front of and close to the feed rolls. Fig. 5 is a plan view, and Fig. 6 an end view of the lower feed roll. Fig. 7 is a sectional side view of the lower feed roll, taken on the line 40 7-7 of Fig. 8. Fig. 8 is a sectional end view of the lower feed roll, taken on the line 8-8 of Fig. 7.

The mechanism herein shown may be mounted and driven independently, or it 45 may be combined either with a machine to which the articles are to be transferred or delivered, or it may be combined with a machine from which the said articles are received. This mechanism is herein shown to 50 be supported upon uprights 52 and 53, which

may be appurtenant to or integral with the framing of the machine to which the present mechanism is applied. The mechanism is shown to be driven by a train of gears, receiving its motion from the gear 46, which 55 meshes with the gear 93 secured to the shaft 62, which is provided with the gear 45 meshing with the gear 43, through which rotary movement is communicated to the delivery rods 41. Rods 44 may be employed to attach the uprights 52 and 53 to the machine carrying the said delivery rods 41, from which the blanks are herein shown to be received.

The shaft 62 is journaled in the uprights 60 52 and 53, and has secured to it the lower feed roll 61, between which and its co-operating upper feed roll 101 the blanks are received over the plate 42 from the delivery 65 rods 41 of the machine or other appliance 70 40 from which the blanks are delivered to the mechanism of the present invention.

The mechanism to which the blanks are to be delivered by the machine of the present 75 invention is herein represented by the cylinder 10 provided with a gripper 11, by means of which the blank when delivered and gripped to the cylinder may be carried around to other mechanism represented by the rolls 12 and 13, for printing, folding, or 80 otherwise manipulating or operating upon the blanks. The cylinder is shown to be mounted upon the shaft 15 journaled in the uprights 52 and 53, and driven from the gear 46 by a train of gearing, consisting of 85 the gears 93, 103 and 17.

This machine is adapted to operate upon different widths and different lengths of blanks, and to that end is provided with means for compensating for the said differences, retarding the longer or faster blanks, and centralizing those of differing widths so as to deliver their front ends centrally or otherwise uniformly in register with the cylinder 10 and its gripper. 90 In order to thus adjust the various parts of the machine so as to receive the different widths and lengths of blanks and deliver them in proper register to the cylinder 10, the gears 93 and 98 are adjustably secured 95 100

to each other and to the shaft 62, being fixed in their adjusted positions by means of bolts 94 and 95. In the construction herein shown the bolts 95 (Figs. 1 and 2) clamp the gear 93 permanently to the flange 96 of the shaft 62, lying between the gears 93 and 98; and the bolts 94 extend through curved slots in the gear 93 and in the said flange, and are threaded into the gear 98. Loosening the bolts 94 permits the gear 98 and with it the gears 103 and 17 and roll 101 to be advanced or retracted relative to the gear 93, thus correspondingly advancing or retracting the roll 101 to the desired extent for 10 registering its blank gripping portions with the various lengths of blanks to be delivered to it. The adjacent faces of the relatively adjustable parts may, if so desired, be provided with suitable graduations, by means of which the machine may at once be adjusted, without experiment, to deliver the leading end of various lengths of blanks to the desired portion of the surface of the cylinder. The ends of the shafts 62 and 15 may be 20 squared, as shown at 60, and 16, respectively, to facilitate this adjustment of the parts.

It is desirable for certainty and uniformity of action in delivering blanks from the rolls 41 to the common feed rolls 61 and 101, to grip the blank by the latter rolls before it is released from the rolls 41. Since the feed rolls 61 and 101 are generally required to travel faster than the roll 41, the blanks, if delivered directly from one to the other in the ordinary way, without any compensating devices, would be liable to become stretched or torn, or at least to be uncertain or irregular in their registration, because of slipping between one or the other of the two pairs of rolls. To compensate for this difference in speed of the two pairs of rolls, and also for the differences in the length of time during which the blanks are gripped by those rolls, due to their varying lengths, 30 means are provided for pushing back the front end of each blank a definite and predetermined extent, differing for each length of blank, so that the blank may be uniformly gripped at its front end between the faster traveling feed rolls 61 and 101, before its rearward end is released by the delivery rolls 41, without causing any such tension as to tear the blank or to interfere with its correct registration. For this purpose the 40 roll 61 is provided with a registering blade or finger 64, which, as the front end of the blank reaches the feed roll 61, pushes that leading end backwardly, thus bending or buckling the blank and providing an amount of slackness equaling or exceeding that which will be taken up by the faster traveling feed rolls between the time that they grip the blank and the time that the latter is released from the delivery rolls 41. A 50 suitable portion of the periphery of the roll

61 or the roll 101, or both, is relieved adjacent to the position of the finger 64, so as to receive and guide, but not to grip, the corresponding portion of the blank, leaving it free to be pushed back between the relieved 70 portions of the rolls.

The finger 64 (Figs. 6 to 8) is pivoted on the stud 76, carried by the roll 61, and has gear teeth 75 cut in its hub which mesh with the teeth of the sector gear 74 secured to the shaft 65 journaled in the roll 61. Oscillatory movement is imparted to the finger 64 during the rotation of the roll 61 by means of the arm 66 secured to the outer end of the shaft 65 and held by the spring 73 80 against the stationary cam 68. An anti-friction roller 67 is preferably employed between the arm 66 and the cam 68. The hub of this cam extends through, and is supported by the upright 52 concentrically with the shaft 62, and may, as herein shown, form a bearing for that shaft. In order to adjust this part of the mechanism to blanks of widely differing length as well as to allow of adjustment for lesser variations in blanks 90 of the same nominal length, the cam 68 is made circumferentially adjustable, the outer end of its hub being provided with a worm gear 69 (Figs. 1 and 3) which meshes with the worm 70 journaled in the bracket 72 supported on the upright 52. The shaft of the worm 70 is provided with a knurled knob or handle 71. By turning the worm in either direction, rotary movement may thus at any time be imparted to the worm gear 69 in 100 either direction; and the circumferential position of the cam 68 be thereby adjusted in either direction relative to the rotation of the roll 61. Obviously, this adjustment may be made not only while the machine is stationary, but also when it is in motion, which will frequently be found of great advantage in making accurate adjustments under actual running conditions. In addition to thus adjusting the timing of the movement of the finger 64 relative to the rotary movement of the roll 61, the position of the finger 64 may be varied by loosening the clamp screw 20 of the arm 66. The shaft 65 and consequently its connected finger 64 may be 110 slipped to different positions of its movement shown by a dot-and-dash arc in Fig. 8, and secured in the adjusted position by tightening the clamp screw 20.

The forwardly projecting free front ends 120 of the blanks are liable to be deflected sideways more or less, especially when pushed backwardly, as above described. As a means for registering the blanks centrally, or deflecting them laterally to any desired position, a pair of centralizing fingers 79 (Figs. 5 to 8) are provided, which are mounted for movement toward each other, as the blank passes to the roll 61, so that the edges of such blanks as may be out of center or may 130

require to be deflected are engaged by one or the other of these fingers, and pushed laterally to the desired position. These fingers are pivoted on the studs 80 carried by the blocks 81 held in the support block 82, which is fitted into a recess provided for it by cutting away a portion of the periphery of the roll 61, to which it is secured. The hubs of the fingers 79 are provided with sector gears 83 which mesh with the teeth 77 cut in the hub of the registering finger 64. The motion of the latter thus serves to impart the required movement of the fingers 79. In order to provide adjustment for varying widths of blanks the pivot blocks 81 are fitted to slide in ways provided in the support 82. The right and left hand screw 84 passes through holes adapted for it in the sliding blocks 81, and is secured against endwise movement by the block 86, which fits between the two collars 85 and is secured to the support 82. Motion imparted to the screw 84 by means of the knurled knob 87 serves to draw together or separate the two fingers 79, the length of the teeth 77 permitting the necessary sliding movement of the sectors 83. A check nut 88 secures the parts in any desired position of adjustment.

The upper feed roll 101 is journaled in the uprights 52 and 53 and may be of any ordinary or preferred form or construction. It is herein shown as a suction roller, for purposes peculiar to the machine shown in the application of which this application is a division. The roll is supported at its right hand end by the shaft 102 (Fig. 1) to which it is secured, and which rotates in the bearing 104. The left hand side of the roll is provided with a long hub 110, which rotates in the bearing 105. The left hand end of the hub has secured to it the gear 103, which meshes with the gear 98 on the shaft 62. The hub 110 is hollow, to serve as a suction pipe or conduit connecting with the pipe 114, through which any suitable suction apparatus may thus be connected with the interior of the roll 101, reaching the periphery of the roll through the slots 113, made in the peripheral wall 112, which may be made removable to permit the substitution of other plates or walls having a different arrangement of slots for different purposes. The roll 101 is provided around one portion of its periphery with the presser feet 106, which are arranged in a series of pairs, one at each end of the roll, as shown in Fig. 1, each presser foot being provided with a spring 107. These independent presser feet pressing against the periphery of the lower acting roll 61 hold the blanks firmly and independently at different portions of their surface, in spite of variations that may occur in their thickness, due to being folded, or for any other reason. The peripheral portions of the presser feet which bear

against the roll 61 are curved in substantial conformity with the circular path of their travel; and they are preferably separated only to a sufficient extent to insure their free, independent action. Hence the gripping action of the successive presser feet upon the blank is practically continuous.

Disposed between the feed rolls 61 and 101, and adjacent to the cylinder 10 is a deflecting plate 21, supported on the rod 22, which is supported in any convenient way from the adjacent framing. This plate serves to deflect the blanks from between the rolls 61 and 101 to the adjacent surface of the cylinder 10; and to enable it to do this positively, the cylindrical surface of the roll 61 is provided with grooves or slots 63, into which fit corresponding projections of the deflecting plate 21.

The operation of the mechanism is as follows:—Blanks are passed through feed rolls 41 over the blade 42 to the roll 61. If the blank is delivered in advance of its proper position, its leading end runs against the finger 64, which pushes it backward to a suitable extent, while the rolls 41 continue to feed forward the portion still gripped by them, thus creating a slack in the blank to varying extents, according to the length of the blank and its rapidity of travel. At the same time, or at any suitable time before the blank is gripped between the rolls 61 and 101, the centralizing or lateral deflecting fingers 79 are brought into operation, and centralize or deflect the blank to the desired position. The leading end of the blank is then seized between the presser feet 106 and the roll 61, thus holding it and passing it forward securely in the path to which it has been guided by the fingers 64 and 79. The leading end of the blank passing over the plate 21 is deflected to the cylinder 10 and seized by the gripper 11, or is delivered to any other mechanism for printing, cutting, folding, or otherwise manipulating or operating upon the succeeding blanks.

The various terms herein employed to denote directions and positions are employed in their relative and not their absolute sense, inasmuch as any of the parts may be reversed, inverted or transposed in many ways that will be obvious to the mechanic or designer. The mechanism shown and described may also be modified as to dimension, amplitude of movement, and in many other ways to suit different sizes or kinds of blanks, or to meet various conditions.

We claim as our invention:—

1. The combination, in mechanism for transporting bag blanks, of a pair of rotary feed rolls for gripping and feeding the blanks forward between them, having a relieved portion to admit the blanks between them without gripping, and adjustable driving means extraneous to said rolls to enable

- the latter to be adjusted circumferentially to vary the position of the gripping surfaces relative to the driving means.
2. The combination, in mechanism for transporting bag blanks, of a pair of rotary feed rolls for gripping and feeding the blanks forward between them, having a relieved portion to admit the blanks between them without gripping, driving means adjustably connected with the said rolls to enable their gripping surfaces to be adjusted circumferentially, and a registering member coacting with the said rolls to retard the travel of the leading ends of the blanks and register them with the gripping surfaces of the rolls.
3. The combination, in mechanism for transporting bag blanks, of a pair of rotary feed rolls for gripping and feeding the blanks forward between them, having a relieved peripheral portion to admit the blanks between the rolls without gripping, a registering member coacting with the said rolls to retard the travel of the leading ends of the blanks, means for operating the said registering member, and means for adjusting the said operating means to vary its time of operation relative to the gripping surfaces of the rolls.
4. The combination, in mechanism for transporting bag blanks, of a pair of rotary feed rolls for gripping and feeding the blanks forward between them, and having a relieved peripheral portion to admit the blanks between the rolls without gripping, a registering member revolving and coacting with the said rolls to retard the travel of the leading ends of the blanks, relatively fixed means for operating the registering member, and means for circumferentially adjusting the said operating means, whereby the time of operation of the said registering member may be varied during its revolving movement.
5. The combination, in mechanism for transporting bag blanks, of a traveling blank carrier for receiving and gripping the blanks, a revolving registering member coacting with the said carrier to move the leading ends of the successive blanks into register with the carrier, a relatively fixed cam for operating the registering member, and means for adjusting the cam circumferentially to vary the time of the registering movement.
6. The combination, in mechanism for transporting bag blanks, of a revolving blank carrier for receiving and gripping the blanks, a revolving registering member coacting with the said carrier to move the leading ends of the successive blanks into register with the said carrier, a relatively fixed cam for operating the registering member, means for adjusting the cam circumferentially to vary the time of the reg-

istering movement, and means including a worm wheel and worm for adjusting the said cam circumferentially during the revolving movement of the registering member.

7. The combination, in mechanism for transporting bag blanks, of a traveling blank carrier provided with means for gripping the blank, a pair of centralizing fingers coacting with the blank carrier and disposed on opposite sides of the blank, and means for moving the said fingers toward each other to centralize the successive traveling blanks relative to the support, prior to the gripping operation.

8. The combination, in mechanism for transporting bag blanks, of a traveling blank carrier provided with means for gripping the blanks, a pair of fingers mounted upon the blank carrier for movement toward and from each other upon the opposite sides of the blank, and means for moving the fingers toward each other to register the blank laterally of the support prior to the gripping operation.

9. The combination, in mechanism for transporting bag blanks, of a rotary blank carrier, means for gripping the blanks to the carrier, a pair of fingers pivotally mounted upon the said carrier, and projecting upon opposite sides of the blank, and means for swinging the said fingers toward each other to move the blank into proper lateral register upon the carrier prior to the gripping operation.

10. The combination, in mechanism for transporting bag blanks, of a traveling blank carrier, means for gripping the blanks to the carrier, registering fingers coacting with the carrier, and means for operating the said fingers to move the blank rearwardly and sidewise into proper register with the carrier.

11. The combination, in mechanism for transporting bag blanks, of a traveling blank carrier provided with means for gripping the blanks, registering fingers carried by the blank carrier, and means for moving the said registering fingers to move the blank rearwardly and laterally into proper register with the blank carrier.

12. The combination, in mechanism for transporting bag blanks, of a rotary feed roll, means for gripping the blanks upon the said roll, registering fingers mounted upon the said roll, and means including a stationary cam for effecting the registering movement of the said fingers.

13. The combination, in mechanism for transporting bag blanks, of a rotary feed roll, means for gripping the blanks upon the said roll, registering fingers mounted upon the said roll, means including a stationary cam for effecting the registering movement of the said fingers, and means for adjusting

the said cam circumferentially relative to the roll to vary the time of operation of the registering fingers.

14. The combination, in mechanism for transporting bag blanks, of a traveling blank support, means for gripping the blanks to the support, lateral registering fingers coacting with the support and disposed upon opposite sides of the blank, means for moving the said fingers toward each other to move the blanks laterally into register with the carrier, and means for adjusting the said fingers toward and from each other to vary the distance between them at their inner registering position.

15. The combination, in mechanism for transporting bag blanks, of a rotary blank carrier, lateral registering fingers pivotally supported upon the rotary carrier and disposed upon opposite sides of the blank, and means for moving the pivotal supports of the fingers toward and from each other to adjust the said fingers to different widths of blanks.

16. The combination, in mechanism for transporting bag blanks, of a rotary blank carrier, centralizing fingers pivotally supported upon the carrier, and extending upon opposite sides of the blank, pivotal supports for the fingers mounted for movement toward and from each other to suit the

different widths of blanks, and driving means for operating the said fingers, including a tooth gear meshing with gear teeth appurtenant to the said fingers.

35

17. The combination, in mechanism for transporting bag blanks, of a rotary blank carrier, lateral registering fingers pivotally supported upon the blank carrier and extending upon opposite sides of the blank, means for moving the pivotal supports of the said fingers toward and from each other to suit different widths of blanks, and means for rocking the said fingers toward and from each other, including a gear mounted 40 for oscillation upon an axis at one side of and parallel with the direction of adjustment of said fingers, and meshing with gear teeth appurtenant to the said fingers, whereby the working positions of the said fingers 45 may be adjusted toward and from each other, without disengaging them from their operating means.

In testimony whereof we have signed our names to this specification in the presence 50 of two subscribing witnesses.
